DIE CASTING MACHINE

Harry J. Kalajian, Detroit, Mich.

Application October 6, 1939, Serial No. 298,278

1 Claim. (Cl. 22—70)

This application relates to die casting machines and more particularly to improvements in the mounting arrangements for the pumps or goosenecks and the pump actuating cylinders commonly employed with such machines.

Generally speaking the mounting arrangement hereof is such that in a die casting machine having a die plate adjacent the melting pot of the machine, the pump or gooseneck and the cylinder are mounted directly on the die plate above the melting pot, and the cylinder above the pump or gooseneck.

For a more detailed description of the mounting arrangement hereof, reference may be had to the following specification which describes in detail the mounting arrangement illustrated in the appended drawing; in this drawing,

Figs. 1 and 2 are side and front elevations of parts of a die casting machine showing both the pump or gooseneck and the cylinder as mounted, one below the other, and both on and in front of a die plate.

Referring to the drawing, it will be observed that it shows as part of a die casting machine, a die plate 10 adjacent and above a melting pot 11 containing a batch of molten metal, gobs of which are to be pumped upwardly from the pot to the inlet port of the die plate of the machine in a manner well known to those acquainted with the art of die casting. Projecting forwardly from the front of the die plate 10 are rigid elongated supports 12—13 in the nature of threaded bolts, four being utilized in the embodiment illustrated. The lowermost pair of such bolts, referenced 12, pass through holes formed in suitable bosses 14 at the upper corners of the pump or gooseneck 15 whose lower end is submerged in the molten metal within the pot 11 and whose discharge spout 16 terminates in a nozzle 17 projecting into an inlet port (not illustrated) formed in the die plate. Suitable nuts 18 threaded on the bolts 12 anchor the gooseneck in place on these bolts and thus provide a firm and sturdy support for the pump with the latter carried directly by the die plate and adjustable on the bolts towards and from the die plate by manipulation of the nuts on the bolts.

The uppermost part of bolts, referenced 13, pass through holes in suitable bosses 19 of a cylinder bed 20 forming the lower part of the actuating cylinder 21 for the pump or gooseneck of the machine; suitable nuts 22 threaded on the bolts 13 rigidly secure the cylinder in place on these bolts with the result that the entire cylinder is firmly and rigidly supported directly by the die plate, in place above the pump or gooseneck.

For minimizing the cantilever action on the bolts 12—13, by tying together the free ends of the upper bolts to the free ends of the lower ones, links or struts 23 are provided. These have holes through which pass the free ends of the bolts 12—13 and nuts threaded on the bolts firmly anchor the links or struts in place on the bolts.

Within the cylinder there reciprocates a piston 24 actuated from an air supply line 25 entering the cylinder, and having its piston rod 26 coupled by a releasable coupling 27 to the plunger rod 28 which terminates in a plunger 29 reciprocating within the pump or gooseneck.

On the surfaces of the cylinder, the cylinder bed, and the pump or gooseneck are placed suitable markings, indicated by the vertically aligned "X" marks on the vertical center line of the cylinder, cylinder bed, and pump or gooseneck. When the pump or gooseneck is properly located with respect to the die plate so that its nozzle is in proper juxtaposition to the inlet port of the die plate, and the four aligning marks indicated are properly aligned, assurance will be had that the cylinder and the pump actuated thereby are in proper alignment, with relative adjustment being provided and maintained by manipulation of the nuts on the bolts.

The advantages of the mounting arrangement herein disclosed will readily be apparent. Among such advantages will be enumerated the following. By release of the releasable coupling and by removal of certain of the nuts of the lower bolts, the pump or the gooseneck may be removed readily from or applied readily to the machine without requiring any manipulation whatever of the cylinder and its parts and without requiring any disturbance of the air supply line.

Further, due to the free air space between the cylinder and the pump, transfer of heat from the pump to the cylinder is reduced to a minimum. Further, the ease of maintaining accurate alignment between the cylinder and the pump in all directions is in no way impaired by the fact that the cylinder and pump are not made in one unitary casting.

Further, because they are not made in one unitary casting, replacement of the pump and repair and cleaning thereof when clogged may be effected without requiring the disturbance of the cylinder in any respect whatever and with in no way affecting the existing cylinder and at an expense far below the expense involved in performing similar operations on presently known constructions. Still further, due to the simplicity of the mounting arrangement, the ease of removing

and applying pumps or goosenecks is not affected to any marked extent by splatterings of molten metal from the machine, as contra-distinguished from presently known constructions where access to the elements which control removal of the pumps or goosenecks is impeded by the existence of splatterings of molten metal.

5 The simplicity of my mounting arrangements renders it unnecessary to go into further detail as to such mounting arrangements and the advantages of the same. Therefore, reference is now made to the claim which follows for a determination of the invention embodied in the herein illustrated die casting machine.

10 15 I claim:

In a die casting machine, a die plate having a forwardly exposed surface, in front of, adjacent, and below which is a molten metal pot, a pump or gooseneck having an inlet port submerged in the 20 pot and having a discharge nozzle in discharge cooperation with the die plate, and formations on

the die plate and pump cooperating for detachably securing the pump directly on and in front of the die plate and above the pot, whereby the pump is supported directly from the die plate, and an actuating cylinder for said pump, and formations on the die plate and cylinder cooperating for detachably securing the cylinder directly on and in front of the die plate and above the pump, whereby the cylinder also is supported directly from the die plate, each set of formations comprising bolts fixed in and projecting forwardly from the die plate, and holes in the pump or the cylinder through which pass the bolts, and nuts threaded on the bolts, and links or struts connecting the free ends of the bolts to tie such free ends to one another, there being a relatively large clear space between the lower part of the cylinder and the upper part of the pump whereby a transfer of heat from the pump to the cylinder is reduced to a minimum.

25 30 HARRY J. KALAJIAN.
